LETTERPLATE ASSEMBLY FOR FLUORESCENT TUBES

Stanis Sierpin, 2266 E. Kirby, Detroit, Mich.

Filed July 11, 1960, Ser. No. 42,097

2 Claims. (Cl. 40—131)

This invention relates to a letterholder construction for signs and more particularly to a letterholder adaptable for mounting upon fluorescent lighting tubes.

It is the object of the present invention to provide a letterholder adapted to have removably positioned thereon a letterplate, with suitable lettering thereon, whereby a combination of these holders with letters mounted thereon, or other message when slidably provisioned upon one or more fluorescent illuminating tubes provides an illuminated sign.

It is the further object of the present invention to provide a novel form of letterholder housing consisting of a hollow apertured boxlike formation having one or more longitudinally opposed apertures in its side walls to slidably receive one or more fluorescent tubes forming the part of a lighting fixture, providing a means for holding the letterholder upon the lighting tube.

It is a further object of the present invention to provide a novel form of letterholder assembly with means for removably receiving a particular letterplate for retaining the same upon a letterholder but at the same time providing for readily removable or replacement thereof.

It is an object of the present invention to provide a letterholder housing wherein letterplates may be removably provisioned and wherein one or more letters may be applied to a particular letterplate, and wherein a plurality of said letterholder housings may be slidably provisioned upon one or more illuminating tubes for the purpose of defining an advertising message and wherein the tubes are arranged rearwardly of the letters for the purpose of providing illumination to the said letterplates.

It is contemplated in this instance that the letterholder plates may be in the nature of opaque plastic material or the like and wherein the letters formed therein may be of clear plastic, or may be apertures therein through which the light source is readily discernible to the observer to thus provision the required lettering or wording, as the case may be.

These and other objects will be seen from the following specification and claims in conjunction with the appended drawing in which:

FIG. 1 is a front elevational view of one form of the present letterholder housing as mounted upon a pair of fluorescent tubes, fragmentarily shown.

FIG. 2 is a fragmentary section taken on line 2—2 of FIG. 1.

FIG. 3 is a fragmentary section taken on line 3—3 of FIG. 1.

FIG. 4 is a front elevational view of a slightly different form of a sign holder.

FIG. 5 is a section taken on line 5—5 of FIG. 4.

FIG. 6 is a section taken on line 6—6 of FIG. 5.

It will be understood that the above drawing illustrates merely a preferred embodiment of the invention and that other embodiments are contemplated within the scope of the claims hereafter set forth.

Referring to the drawing and particularly FIGS. 1, 2 and 3, there is shown one form of sign holder. A pair of vertically aligned fluorescent illuminating tubes 12 have their terminal ends 13 mounted within a pair of upright conventional supports 11, which are suitably mounted or secured to a wall surface as at 14.

The present sign holder generally indicated at 15, is adapted to be slidably mounted upon the pair of tubes 12,

2

as particularly illustrated in FIG. 2. The present letterholder includes a pair of upright parallel spaced end walls 16 having a pair of vertically aligned circular apertures 17 adapted to slidably and cooperatively receive the respective tubes 12, as best illustrated in FIG. 2.

The respective apertures 17 defined in the end walls 16 terminate in the diverging cutouts or gates 18, said end wall 16 also being horizontally slotted as at 19 for ventilation.

10 The letterholder 15 also includes the respective parallel spaced top and bottom walls 20 completing the boxlike assembly and defining the rectangular aperture 21 at the front thereof, and arranged inwardly thereof the rectangular opening 26 adapted to cooperatively receive the upright letterplate 27 as hereafter described upon which suitable indicia 28 is provided as for example the lettering shown.

It is contemplated the letterplate, for example, may be of an opaque material or opaque plastic as at 27, and 20 with the letters therein provided by transparent or translucent portions as at 28 to define the lettering shown. It is contemplated also as a part of the present invention that the letterplate 27 may merely have cutouts therein to define the respective letters or series of letters to make 25 up the intended sign to be mounted upon the fluorescent tubes.

Projecting inwardly from the respective top and bottom walls 20 and side walls 16 is the continuous inwardly tapered retaining flange 22, adapted to retainingly engage the 30 continuous outer edge of the letterplate 27 upon one side thereof. Transverse horizontally disposed inwardly directed tapered flanges 25 project respectively from the upper and lower walls 20 of the housing and are adapted to retainingly engage interior upper and lower edge portions of the respective letterplate 27.

It is noted for example in FIG. 2 that the spaced pair of flanges 25 are of less extent than the corresponding front flange 22 so that the letterplate 27 may be snapped into the defined rectangular slot 26 from the interior of 40 the letter housing. The letterplates 27 are of a flexible material such as metal or plastic, like polystyrene, for illustration, and accordingly are self-supporting once projected within the retaining slot 26 which is arranged in an upright plane with respect to the front face of the housing. 45 Flanges 25 as a pair could instead be arranged on opposite sides on the interior of the housing rather than at the top and bottom.

As viewed in FIG. 1, the righthand side wall 16 of each of the housings adjacent its front surface, has a lateral projection 29. The corresponding opposite side edge of the housing has formed therein an elongated aperture 30. Accordingly, when a pair of the said housings are assembled side by side, the projection 29 of one assembly cooperatively nests within the recess 30 in the opposite side 55 of the adjacent assembly as best shown in FIG. 1 to thus create an innerlock between the sign holders.

In operation the sideholders must be slidably provisioned over the ends of the tubes 12. For this purpose, the end wall gates 18 are laterally aligned with the individual tube holders 11 and the housing slidably positioned thereon.

In view of the fact that a pair of vertically spaced tubes 12 are shown in FIG. 1 and FIG. 2, letter housings 15 are retainingly provisioned in the upright position shown.

65 A slight variation is shown in FIGS. 4, 5 and 6 wherein the letter housing 31 is more simplified and is adapted for mounting upon a single tube. For this purpose there is provided the upright parallel side walls 32 with arcuate apertures 33 therein adapted to cooperatively receive a fluorescent tube. The aperture 33 opens in the rearwardly extending gate 34. The housing includes the re-

spective top and bottom walls 35 which towards their forward ends and in conjunction with the end walls 32 define the rectangular opening 36 in the front of the casing.

Rearwardly thereof and of slightly increased dimension is the rectangular opening 37 within which is positioned a corresponding letterplate 43 with suitable indicia or lettering or numbers, or the like, 44, as above described.

The letterplate 43 at its rear is retained within the rectangular opening 37 by the continuous flange 38 which extends inwardly from the top and bottom walls 35 and side walls 32. Front portions of the letterplate 43 are retained at their top and bottom by the inwardly tapered pair of flanges 40 which additionally form a part of the top and bottom walls 35.

It is contemplated as a part of the present invention that the said letterplate may be manually projected with a slight flexing of the top and bottom edges of the letterplate into the slot 37 from the front of the casing. This is provided for by the outer tapered top and bottom flanges 40 being of smaller extent than the corresponding rear continuous flange 38.

In the present construction employing a single tube for mounting on the letterhousing, normally some means should be employed for retaining the said housing in the upright position shown in FIG. 5.

It is contemplated that as a part of the present invention that the said housing may engage the wall surface as indicated at 14. Accordingly, as shown in FIG. 5, the assembly or housing 31 is retained in the upright position shown by the rear end portions of the side walls 32 engaging the wall surface 14.

Instead of employing the pair of top and bottom flanges 40 of FIG. 5, there may be used a pair of side flanges for retaining a pair of outer edges of letter plate 43 with respect to the inner continuous flange 38.

A translucent strip 41 of plastic material of any desired color may be employed as in FIG. 5 to give color to the lettering on the letter plate 43. In operation, the housing 31 is slid over tube 12 with the tube support 11 received within gate 34. Thus the sign housing is mounted on the tube without disconnecting said tube.

Having described my invention, reference should now be had to the following claims.

I claim:

1. In combination a letterplate mounting device and a fluorescent tube supported upon a flat wall by a pair of fluorescent tube end supports each having an end which

engages and connects with one of the ends of the tube and an opposite end secured to the wall, the end supports each being arranged substantially horizontally and being elongated in its horizontal direction and of a uniform vertical height which is less than the diameter of the tube, the end supports thus being radially arranged relative to the tube axis and normally arranged relative to the wall and holding the tube parallel to but spaced a short distance from the wall; said letterplate mounting device comprising a box-like housing having a vertically arranged front wall, centrally apertured to form a picture frame, top and bottom horizontal walls, identical vertical end walls, and an open back, all of the walls being rigid and immovably connected together; said end walls each having a circular opening of a size to slidably receive the fluorescent tube, the openings being horizontally aligned; each end wall having a notch horizontally extending from its rear edge into its opening and axially aligned with the center of its opening, the width of the notches in the vertical direction being slightly greater than the vertical height of the end supports, the circular edges defining the openings being otherwise uninterrupted and engaging the periphery of the tube in a circular line contact, whereby the housing is mounted upon the fluorescent tube by sliding it endwise upon the supported fluorescent tube with the end wall openings slidably receiving the tube and the notches slidably passing the support for thus holding the housing upon the tube; and means for mounting a letterplate within the front wall picture frame forming aperture.

2. A construction as defined in claim 1, and said end walls, above and below the notches, extending rearwardly a sufficient distance to bridge the space between the tube and flat wall so that their ends contact the flat wall above and below the axis of the tube for non-rotatably holding the housing relative to the tube.
